UNITED STATES PATENT OFFICE.

WILLIAM B. C. SASSE, OF SPEARFISH, SOUTH DAKOTA.

CLOTHESPIN.

1,357,121.

Specification of Letters Patent. Patented Oct. 26, 1920.

Application filed January 20, 1919. Serial No. 272,047.

To all whom it may concern:

Be it known that I, WILLIAM B. C. SASSE, a citizen of the United States, residing at Spearfish, in the county of Lawrence, State 5 of South Dakota, have invented certain new and useful Improvements in Clothespins; and I do hereby declare the following to be a full, clear, and exact description of the invention, such as will enable others skilled 10 in the art to which it appertains to make and use the same.

This invention relates to new and useful improvements in clothes pins.

One object of the present invention is to 15 provide a novel and improved device of this character which is formed from a single length of non-corrosive spring wire.

Another object of the invention is to provide a clothes pin of novel construction 20 which is capable of gripping the clothes line and clothes at the same time and which is arranged to remain on the clothes line.

Another object of the invention is to provide a novel and improved structure which 25 is capable of engaging the clothes and line at the same point or gripping the clothes at one point and the line at another.

Other objects and advantages will be apparent from the following description when 30 taken in connection with the accompanying drawing.

In the drawing:

Figure 1 is a side elevation of the clothes pin in engagement with the line and clothes, 35 the line being shown in section.

Fig. 2 is a front or edge view of the device in the position of Fig. 1.

Fig. 3 is a side elevation of the pin removed from the line.

Fig. 4 is a side elevation of the pin suspended in an inverted position on the line, and in engagement with a piece of fabric.

Referring particularly to the accompanying drawing the pin is formed from a single 45 length of suitable non-corrosive spring wire, the ends of which are secured together at 10. The wire is bent to form the large ring 11, at one end of the device and the smaller ring 12 at the other end, the intermediate portions or legs 13 connecting the ends of the 50 rings. The portions of the legs 13, adjacent

their connection with the smaller ring, are bent in opposite directions away from each other, thus producing, in the smaller ring, a single helix coil or turn which has great 55 resiliency. The intermediate portions of the legs 13 are outwardly and oppositely bowed, as shown at 14 for the reception of the clothes and line, as clearly seen in Fig. 1 of the drawing. By reason of the apparent twist to the upper ends of the legs, there is formed therebetween a wedge opening 15, into which the clothes may be inserted, in addition to the gripping between the bowed portions 14. Thus the clothes are held 60 firmly on the line.

It will also be noted that by reason of the fact that the larger ring is completely closed, the clothes line must be passed through the clothes pin, thus retaining the 70 pin on the line, and preventing the loss of same.

It will be noted that when the pin is being engaged with the clothes and line, the larger ring will be spread open while the 75 smaller ring will be drawn under tension toward closed position, thereby producing a double grip which insures the proper engagement and retention of the clothes on the line.

What is claimed is:

A clothes pin formed from a single length of wire and including a large closed ring and a small closed ring lying in spaced relation in the same plane, legs extending in 85 parallel relation and in the plane of the rings and being connected at their ends to the rings, the ends which connect to the small ring being crossed at such points of connection, the intermediate portions of the legs being outwardly bowed, said legs being adapted, at times to engage over a clothes line and garment and to receive a garment, without the line therebetween, below the line, at times, with the larger ring 90 engaged in supporting relation to the line 95

In testimony whereof I affix my signature in the presence of two witnesses.

WILLIAM B. C. SASSE.
